ATTORNEY

UNITED STATES PATENT OFFICE.

HUGH VINCENT McPARTLAND, OF NEW YORK, N. Y., ASSIGNOR OF ONE-HALF TO
OSWIN C. MOLL, OF BROOKLYN, NEW YORK.

OZONATOR.

Application filed August 16, 1927. Serial No. 213,369.

The present invention is concerned with improvements in ozonators, an object of the invention being to provide an ozonator in which the usual air gap between electrodes is entirely eliminated, and an ozonator of extremely simple, practical construction which will be highly efficient in use, in that a maximum amount of oxygen condensing and ozone generating surface is provided in a minimum amount of space due to the use of closely arranged perforations in the electrodes which cause a plurality of relatively intense corona discharges, and a rapid formation of ozone.

Another object of the invention is to provide a unit adapted to be associated with the air intake of a carburetor and which includes in combination an ozonator and moistener so that air entering the carburetor is thoroughly ozonated and damped, and peculiarly suited for supporting the combustion of highly atomized or other types of fuel oil.

Other objects of the invention are to provide an ozonator which is well suited to the requirements of economical manufacture.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a plan view of an ozonator embodying the present invention with parts of the electrode and dielectric laminations broken away for the sake of clearness.

Fig. 2 is a longitudinal sectional view on the line 2—2 of Fig. 1.

Fig. 3 is a sectional detail on the line 3—3 of Fig. 1.

Fig. 4 is a view partly in side elevation and partly in section showing an ozonator and moistening unit adapted to be associated with the usual intake of a carburetor.

It is to be understood at the outset that the accompanying drawings are more or less diagrammatic, and that while I have shown comparatively simple forms of electrodes interlaminated with dielectric sheets it may be desirable in many instances to use single electrodes comprising a great number of electrode sheets instead of simply one or two.

In the drawings I have used the reference numbers 10 and 11 to designate the electrodes.

The electrode 10 is in the nature of a single imperforate sheet of suitable conductive material such for instance as extremely thin metal or tin foil. It is connected as by a wire 12 to a suitable coil such as the coil 13 in Fig. 4 energized from the battery 14.

The electrode sheet 11 is disposed between a pair of relatively thin dielectric sheets 15 of mica or equivalent material. The electrode 10 includes two spaced sheets of conductive material such as tin foil, which sheets overlie the outer surfaces of the mica sheets 15 and are connected by a wire 16 to the other end of the coil 13.

The two sheets of the electrode 10 are perforated as indicated at 10^a, the perforations being arranged closely together and the perforations of one sheet being staggered relatively to the other as best seen in Fig. 1.

Even without any current passing through the electrodes, there will be a tendency for oxygen to condense on the outer electrode and on the exposed surfaces of the mica dielectrics. When the current is on, such condensation will of course be materially accentuated and increased to an extent where the small corona discharge emanating from the rim of each and every perforation and passing from one electrode to the other will cause generation of ozone. This silent electrical discharge does not have to pass through any air gap as is the case with the ozonators now employed, and the discharge occurring at all of the perforations insures generation of ozone over a wide area.

While I have not definitely established my theory on the point, the discharge seems to follow the law of inverse squares. That is, if the dielectric is twice as thick between the metal plates the discharge is one-fourth as strong; and three times as thick, only one-ninth as strong, etc.

In Fig. 4 I have shown diagrammatically a unit for application to the air intakes of internal combustion engines, especially for application to intake of the carburetors. In this view, a box 20 contains a number of the ozonator units above described, over which the incoming air is passed and in which ozone is generated. From the box 20 the air and ozone are carried through a moistening chamber 21 and passed over a number of wicks 22 dipping in a well 33, thence to the air intake pipe 24 of the carburetor. The moist ozonated air is of course excellent for mixture.

with the atomized gasolene or other hydro-carbon fuel employed.

The electrodes while illustrated as of plate form, might be in the nature of various types 5 of conductive pastes or powders, printed, painted or otherwise applied to the faces of the dielectric. Conductive wire or metal strips might also serve as electrodes, and I do not wish to limit myself in this respect.

10 Various changes and alterations might be made in the general form and arrangement of the parts described without departing from the invention. Hence I do not wish to limit myself to the details set forth, but shall consider myself at liberty to make such changes 15 and alterations as fairly fall within the spirit and scope of the appended claims.

I claim:

1. An ozonator comprising a pair of thin 20 plate electrodes interleaved with each other and with thin sheets of dielectric material,

the outer electrode sheet having a plurality of apertures therein.

2. An ozonator comprising a pair of thin 25 plate electrodes interleaved with each other and with thin sheets of dielectric material, the outer electrode including a pair of sheets lying on opposite sides of the pack and having apertures therein.

3. An ozonator comprising a pair of thin 30 plate electrodes interleaved with each other and with thin sheets of dielectric material, the outer electrode including a pair of sheets lying on opposite sides of the pack and having apertures therein, the apertures of one 35 sheet being staggered relatively to the apertures of the other.

Signed at New York in the county of New York and State of New York this 15th day of August A. D. 1927.

HUGH VINCENT McPARTLAND.
